UNITED STATES PATENT OFFICE.

HARRY F. CRECELIUS, OF READING, PENNSYLVANIA.

DESIGN FOR A BADGE OR CHARM.

SPECIFICATION forming part of Design No. 21,368, dated March 8, 1892.

Application filed January 14, 1892. Serial No. 418,117. Term of patent 7 years.

To all whom it may concern:

Be it known that I, HARRY F. CRECELIUS, a citizen of the United States, residing at Reading, in the county of Berks, State of Pennsylvania, have invented a new and original Design for Badges or Charms, of which the following is a specification.

The lower portion a represents an elk-tooth provided with an upper section or shell b, the outline of which is blended into that of the tooth, so as to form an irregular shield-shaped design. The main face of the upper section b is provided with an elk-head d, the main part of which extends below the shell and in contact with the face of the tooth portion, while the upper part of the head, with the horns and spreading antlers, spreads out in bold relief on the main face of the section b, leaving a flat surface c, however, between the antlers, upon which is placed suitable lettering. The upper edge e is scalloped and ornamented and suitable means for attachment are provided. 25 The main feature on the reverse face of the upper portion b (shown in Fig. 3) is a miniature clock-face, which fills the center between the scalloped edge and the tooth, leaving space on either side for lettering and ornamentation, 30 as shown.

The leading features of the design are the shield shape, comprising the blending together of the tooth portion and the upper section, and the elk-head at the junction of the 35 two portions and extending over each.

What I claim is—

The design for a badge or charm, substantially as herein shown and described.

In testimony whereof I affix my signature in 40 presence of two witnesses.

HARRY F. CRECELIUS.
